UNITED STATES PATENT OFFICE.

FRANCIS W. INDEN, OF DULUTH, MINNESOTA.

RESOPHONE FOR TELEGRAPH INSTRUMENTS.

SPECIFICATION forming part of Letters Patent No. 687,234, dated November 26, 1901.

Application filed January 26, 1901. Serial No. 44,801. (No model.)

To all whom it may concern:

Be it known that I, FRANCIS W. INDEN, a citizen of the United States, residing at Duluth, in the county of St. Louis and State of Minnesota, have invented new and useful Improvements in Resophones for Telegraph Instruments, of which the following is a specification.

My invention relates to what I style a "resophone" for use in connection with telegraph instruments. Its object is to provide means for inclosing the telegraph-sounder and projecting the sound therefrom on predetermined lines or within limited zones.

With telegraph instruments as now used it is customary to expose the sounder, so that the sound is emitted equally therefrom in all directions, and this has been found undesirable where secret messages are sent, in telegraph-offices, where numerous instruments are employed, railroad-stations, where foreign sounds interfere with the receiving of train-orders that require extreme accuracy, in public places, such as the floor of a board of trade, where it is desirable that the messages delivered by the telegraph-sounder be distinctly heard only by the receiving-operator, in newspaper-offices, where the clicking of instruments annoys persons who work within range of the sound emitted by the instrument, and under many other varying conditions where it is desirable to confine the sound of the instrument to a limited space.

To these ends my invention consists of a sound-muffling inclosure wherein the telegraph-sounder is located and which is perforated to emit the sound from the instrument.

In the accompanying drawings, forming part of this specification, Figure 1 is a front elevation of the resophone, shown with its lid open, so as to expose the telegraph-sounder to view, and partly broken away to show the slot in which the lid works. Fig. 2 is a side elevation of the resophone, partly broken away to expose the instrument and shown attached beneath a counter, which is provided with a working table below the instrument; and Fig. 3 is a similar view to Fig. 2, showing the resophone supported by the standard on a swinging arm.

In the drawings, let A represent the telegraph-sounder, B the sounding-box, and C the trumpet for projecting the sound emitted by the sounder from the box.

The telegraph-sounder is placed inside the box and, as shown, is fastened by the screws 2 to the lower side 3. The front side 4 of the box is movable, so that it constitutes a lid or closure, which when open affords ready access to the sounder. This lid has flanges 5, which mortise into the grooves 6 of the box to slide. It is obvious, however, that the lid may be pivoted or hinged to the frame or the box otherwise constructed to enable ready access to the sounder without departing from the principles which I have applied.

As shown, the lid of the box is perforated at 7 to emit the sound from the instrument. This perforation is positioned directly opposite where the sounding-lever 8 when operating strikes the frame 9 and produces the click, so as to be in direct range of the sound thus emitted. The trumpet or sound-magnifier C is secured with its inner and contracted end over the perforation of the lid by screws 11, which pass through its flange 12. The trumpet may project through the lid into the box, if desired, or the box or lid may be formed with a suitable opening for projecting the sound without the use of a trumpet, as shown in the drawings.

The materials used in the construction of the box and trumpet may be metal, wood, or any other substance suitable for inclosing the sounder and projecting the sound therefrom to the ear of the receiving operator and for muffling the sound in other directions.

The electric conducting-wires for energizing the sounder, as shown, are incased in the cable 13, passing through the bushing 14 in the box to the sounder. This cable is flexible, so that the instrument may turn or swing to any desired position without breaking or disconnecting the wires from the instrument.

The box is pivoted to the under side of the counter 15 by the screw 16, which passes through the washer 17 inside the box and the collar and ring 18 and 19 between the box and the lower face of the counter. (Shown in Fig. 2.) By this method of fastening the

resophone may be turned on the pivot to emit the sound in any desired direction to suit the convenience of the receiving operator. The front 20 of the counter carries the working table 21 below the instrument.

As shown in Fig. 3, the box B is pivoted at 22 to the free end of the swinging arm 23, which is journaled on the upper end of the vertical rod or standard 24. In this construction the apparatus may be portable or the standard may be mounted on the table 25 by screws 26. The swinging arm permits the resophone to be turned to any desired position in a horizontal plane. It is obvious the swinging arm may be vertically adjustable on the standard. For many uses this construction is important, as it enables the trumpet to be projected in any desired direction and which at the same time permits lateral, forward, rearward, or vertical adjustment of the box. It is obvious that the size, shape, and dimensions of the different parts may be varied at will and also that the resophone may be attached to a telegraph-receiver in any position.

Having described my invention, what I

claim as new, and desire to protect by Letters Patent, is—

1. The combination with the telegraph-sounder of a sound-muffling box inclosing the same, a cover for opening and closing said box, a sounding-trumpet opening through and projecting from said cover, and a pivoted arm on the free end of which said box is pivotally mounted.

2. The combination with the telegraph-sounder, of a box inclosing the same, said box having a movable side, and a trumpet secured to said side and opening from said box.

3. The combination with the telegraph-sounder, of a box inclosing the same, a sliding side for opening and closing said box and the trumpet opening through and projecting from said side.

In testimony whereof I have signed my name to this specification in the presence of two subscribing witnesses.

FRANCIS W. INDEN.
